UNITED STATES PATENT OFFICE.

GEORGE E. PARKS, OF PILLAGER, MINNESOTA, ASSIGNOR OF ONE-HALF TO JOHN T. PARKS, OF PILLAGER, MINNESOTA.

VALVE FOR CYLINDER PUMPS.

Application filed April 8, 1926. Serial No. 100,756.

This invention relates to certain new and useful improvements in valves for cylinder pumps and has for its primary object to provide a hinged or flap valve associated with a pump cylinder of single piece construction as distinguished from the usual pump cylinder formed of two sections bolted together with the flap valve supported at the connection between the two sections in 10 the pump cylinder.

A further object of the invention is to provide a valve for cylinder pumps wherein a spring ring carrying a flap valve seats into an annular groove formed in the inner 15 wall of a pump cylinder to retain the valve and its support in position in the absence of any fastening devices such as bolts, screws or the like.

A still further object of the invention is 20 to provide a valve for cylinder pumps of the flap type wherein said valve embodies a leather or other elastic body seating on an annular flange forming a valve seat and carrying a metallic plate upon its upper side 25 to provide a weight to insure self-closing of the valve.

With the above and other objects in view 30 that will become apparent as the nature of the invention is better understood, the same consists of the novel form, combination and arrangement of parts hereinafter more fully described, shown in the accompanying drawing and claimed.

In the drawing, wherein like reference 35 characters designate corresponding parts throughout the several views,

Figure 1 is a vertical longitudinal sectional view of a cylinder pump constructed in accordance with the present invention 40 showing the pump cylinder of one piece construction with the improved flap valve operatively positioned therein,

Figure 2 is an enlarged horizontal sectional view taken on line 2-2 of Fig. 1 45 showing the spring ring carrying the flap valve with the ring split and having the split ends directed upwardly and inwardly to overlie the swinging side of the valve to limit upward movement thereof, and

Figure 3 is a detail vertical sectional view taken on line 3-3 of Fig. 1.

The pump cylinder as shown is of one-piece construction and embodies a cylindri-

cal portion 1 having an enlarged bell bottom 2 carrying an annular flange 3 for attachment to a well head or the like and in which cylinder 1 the piston 4 is reciprocably mounted. The valve associated with the pump cylinder is positioned at the connection between the cylindrical body portion 1 and the lower bell bottom 2 and carries a spring device for holding the same in position to the exclusion of extraneous fastening members, such as are employed in connection with a two-piece pump cylinder construction. 55

As shown in Figs. 1 and 3, the lower end of the body portion 1 of the cylinder is provided with an annular groove 5 internally thereof and also an annular flange 6 projecting inwardly from the inner face of the cylinder below and adjacent to the groove 5, the flange 6 constituting a valve seat. 60

The flap valve includes a carrier in the form of a split spring ring 7 having the split ends 8 thereof upwardly and inwardly bent as shown in Figs. 2 and 3 and adapted to be received in the annular groove 5 in the pump cylinder 1. The valve per se includes an elastic body, such as leather 9 carrying upon its upper face a metallic plate 10 that is secured thereto by rivets 11 or the like, while the connection between the valve body 9 and the carrying ring 10 includes straps 12 having their ends secured to the upper and lower sides of the valve body with the looped portions 12^a thereof pivotally supported on the inset portions 13 of the ring 7. 75

With the valve supported as illustrated, 80 the spring ring 7 being confined within the annular groove 5, the valve is prevented from bodily shifting movement within the cylinder while operative flap movements thereof are clearly permitted and limited by 85 the inwardly directed ends 8 of the split ring 7. The weight of the metallic plate 10 upon the upper face of the valve body 9 insures closing movement of the valve while the elastic body 9 of the valve engages the valve seat 6 intimately. The valve and its carrier are readily mounted in position by forcing the same downwardly through the pump cylinder 1 and can be as easily removed in an upward direction. 90

While there is herein shown and described

the preferred embodiment of the present invention, it is, nevertheless to be understood that minor changes may be made therein without departing from the spirit and scope 5 of the invention as claimed.

What is claimed is: —

1. In a valve for cylinder pumps, the combination with a pump cylinder having an internal annular groove, of a flap valve, and a resilient carrier for said flap valve removably received in the cylinder groove.
2. In a valve for cylinder pumps, the combination with a pump cylinder having an internal annular groove, of a flap valve, a resilient carrier for said flap valve removably received in the cylinder groove, and an inwardly directed annular flange on the pump cylinder constituting a seat for said flap valve.
3. In a valve for cylinder pumps, the combination with a pump cylinder having an internal annular groove, of a flap valve, a resilient carrier for said flap valve removably received in the cylinder groove, an inwardly directed flange on the pump cylinder constituting a seat for said flap valve, and a

metallic plate carried by the valve for weighting the same.

4. In a valve for cylinder pumps, the combination with a pump cylinder having an internal annular groove, of a flap valve, a resilient carrier for said flap valve removably received in the cylinder groove, an inwardly directed annular flange on the pump cylinder constituting a seat for said flap valve, said carrier comprising a split resilient ring and said flap valve being pivotally carried by the ring.

5. In a valve for cylinder pumps, the combination with a pump cylinder having an internal annular groove, of a flap valve, a resilient carrier for said flap valve removably received in the cylinder groove, an inwardly directed annular flange on the pump cylinder constituting a seat for said flap valve, said carrier comprising a split resilient ring, said flap valve being pivotally carried by the ring, and the ends of the split ring being directed inwardly and overlying the valve to limit opening movement thereof.

In testimony whereof I affix my signature.
GEORGE E. PARKS.
